G. F. MORSE.
THROTTLE VALVE.

No. 64,690.

Patented May 14, 1867.

United States Patent Office.

GEORGE FREDERICK MORSE, OF PORTLAND, MAINE.

Letters Patent No. 64,690, dated May 14, 1867

IMPROVEMENT IN THROTTLE-VALVES.

The Schedule referred to in these Letters Patent and making part of the same.

TO ALL WHOM IT MAY CONCERN:

Be it known that I, GEORGE F. MORSE, of Portland, in the county of Cumberland, and State of Maine, have invented a new and useful improved Balanced Throttle-Valve for steam engines; and I hereby declare the following to be a full, clear, and exact description thereof, which will enable others to make and use my invention, reference being had to the accompanying drawings, forming part of this specification, in which—

Figure 1 shows a longitudinal section of my invention.

Figure 2, the same with the valve.

Figure 3, an end view.

Figure 4, a transverse section.

My invention has in view a throttle-valve for steam engines which shall, in operation, be so nearly balanced as to lessen the friction, and consists in the arrangement of the parts and an application of the same in the manner I will describe as follows, first referring to the various parts by letters.

a a' show two ports in the body upon one side, and there are two other corresponding ports upon the opposite side in a similar position. These two are clearly shown in fig. 1. *b* shows one of two ports in the valve. The form of the valve, with its two ports, is seen in fig. 4, *A* representing the valve. Two ports, one for the admission of the steam into the casing or cylinder, *D*, and the other for its egress, are made in the cylinder. These are placed in the same positions on opposite sides of the cylinder, and are illustrated at *B*. Upon the top of the valve, and extending its length, is constructed a channel, *d*. In the top of the cylinder is set the bolt *h*, projecting somewhat into the channel or groove, and operating as a guide to the valve motion, and to keep the same from turning. As before specified, the object of my invention is to diminish the friction of the valve within the casing or cylinder. As the steam enters the casing or cylinder, and passes through the ports in the valve, it is also admitted over the valve into the groove *d*, where its presence operates as a counterbalance to the pressure on the under side of the valve through the ports *a a'*; thus the pressure of the valve against the upper side of the casing or cylinder is counteracted by the steam in the channel *d*, and the valve allowed, in consequence, to move with but slight friction.

As seen in the drawing, the valve is cylindrical, the ports are in the lower side of the valve and the valve casing, and the channel *d* is upon the opposite side thereof. The operation and effect of this are to make the valve nearly balanced, thus to lessen the friction, and to keep the valve pressed down on its seat by the elastic quality of the steam in the channel *d*. Without this channel *d* the valve would be pressed upward by the force of the steam entering the ports of the casing, and, in consequence, the valve would not always be kept tight, but with the arrangement of the ports, the form of the valve, its nicely fitting the cylinder, and the application of the channel *d*, the valve is kept tight, wears even, and is held to its position on the seat.

I do not claim constructing a steam-chest with continuous circular ports, both for the induction and exhaustion of the steam, so as to keep a constant and equal pressure of steam upon both ends and the periphery of a cylindrical piston-valve, neither do I claim a piston-valve composed of two heads which fit closely in the bore of a circular steam-chest, and are united by a cylindrical portion of less diameter than the heads, the steam-chest being constructed with circular ports or passages. I wish, still further, to disclaim making openings throughout the length of cylindrical valves which have reciprocating motions in their chests, so as to permit the steam to pass to that end of the chest which is furthest from the induction passage. The devices referred to in the first two disclaimers being exhibited in the patent of Joseph Marks, January 24, 1854, and the last in the patent of C. W. Tremain, September 19, 1865. My invention is intended to embrace simply the arrangement of a cylindrical sliding throttle-valve in the casing, by having the steam openings upon one side, and the channel *d* upon the other, of the valve, in order that the steam upon one side may act as a counterpoise to that upon the other.

What I claim as my invention, and desire to secure by Letters Patent, is—

The arrangement of the partially balanced sliding throttle-valve in its casing, by means of its cylindrical form, and by having the steam openings on one side and the channel *d* on the other side of the valve open to the admission and pressure of the steam, to more than balance the area of the ports, so that the valve shall be pressed against the steam openings in the seat, but with so slight a pressure as to cause but little friction, and require but little force to move it.

GEO. FRED. MORSE.
